(57) **CLAIM**

The ornamental design for an automatic external defibrillator training device, as shown and described.

DESCRIPTION

FIG. 1 is a perspective top view of our automatic external defibrillator training device;

FIG. 2 is a perspective bottom view thereof;

FIG. 3 is a top view thereof;

FIG. 4 is a bottom view thereof;

FIG. 5 is a left side view thereof;

FIG. 6 is a right side view thereof;

FIG. 7 is a front end view thereof; and,

FIG. 8 is a rear end view thereof.

The dash-dot-dash broken lines represent the bounds of the claim, and the evenly spaced broken lines depict portions of the defibrillator that form no part of the claimed design. None of the broken lines form a part of the claimed design.
